METHOD AND APPARATUS FOR THE PRODUCTION OF COMBUSTIBLE GASES FROM LIQUID FUELS

Willy Linder, Essen, Germany, assignor, by mesne assignments, to Koppers Company, Inc., Pittsburgh, Pa., a corporation of Delaware

Application June 12, 1951, Serial No. 231,096

9 Claims. (Cl. 48—62)

The invention generally relates to the continuous production of combustible gases—particularly gases of high calorific value which can also be used as town gas—from liquid fuels such as mineral oil, coal tar oil, brown-coal tar oil, tar oils from low temperature carbonisation, and residues or distillates from the distillation of such or other liquid fuels. More specially the invention relates to a process for the production of combustible gases from liquid fuels wherein the liquid fuel is converted by reaction with oxygen and, if desired, steam in a reaction chamber operating at a high temperature.

It has been already proposed to convert liquid fuels into combustible gases by reaction with oxygen and steam in such a way that the reaction components are injected independently and separately in form of jets into a reaction chamber at high temperature. The gases resulting from such mode of operation, though combustible, do not show such calorific value and such density as have been found to be necessary for using such gases for heating and lighting in place of coal carbonisation gases such as town gas. Another disadvantage of the known manner of operation as described above is to be seen in the face that a rather large amount of elementary carbon such as soot is formed.

In contrast to this prior art the invention consists in the production of combustible gases from liquid fuels in such a way that only a portion of the liquid fuel to be gasified is caused to react directly with oxygen in order to produce continuously gases, preferably combustible gases of high temperature and after that introducing before cooling into the flow of hot gases the other portion of the fuel, preferably in a continuous stream.

This principle of operation according to the invention may be reduced to practice in different ways. One way consists in introducing into the reaction chamber the liquid fuel in finely divided, but liquid, form viz. one portion in mixture with gaseous oxygen and the other portion without addition of oxygen at a place or places which are more or less spaced from the inlet of the fuel-oxygen mixture.

Another mode of realization of the invention consists in vaporizing one portion of the liquid fuel to be gasified by a distillation or any other suitable manner of evaporation in order to produce hydrocarbon vapors for mixing with the flow of hot combustible gases resulting from the reaction with oxygen of the other vaporized portion of the liquid fuel.

The reaction with oxygen of the fuel to be gasified and the following cracking of the hydrocarbons injected into the hot reaction products may be performed in presence of steam, if desired.

The essential advantage of the process according to the invention is to be seen from the fact, that it is possible, when operating in the given manner, to produce valuable gases or mixtures of gases of preferred composition and physical qualities by suitably adjusting the amount of oxygen and, if any, steam to be added to the fuel and the total amount of fuel which is to be

2

converted with oxygen respectively to be introduced into the flow of hot reaction products. Physical qualities to be considered here are the density and the calorific value of the gases produced.

Furthermore the invention allows producing in one operation from liquid fuels a valuable fuel gas of town gas quality.

The mode of operation as described may be performed at normal pressure as well as at increased pressure.

Although the invention is related principally to the treating of liquid fuels it is, however, possible to replace at least part of the liquid fuel by such gaseous fuels the calorific value of which is high because of their contents of high molecular hydrocarbon gases which may be cracked to form permanent gases or low molecular hydrocarbons.

Gases to be considered here are, for instance, natural gases containing propane, butane etc.

In case that the fuel to be treated according to the invention shows a relatively small content in disposable hydrogen the useful fuel gas formed may have a higher density than desired. In order to compensate this undesired property of the valuable gas it is possible to convert by well-known process at least part of the carbon monoxide of the valuable gas into carbon-dioxide and free hydrogen, removing as far as it is necessary out of the gas the carbon dioxide resulting from such conversion by means of washing the gas at increased pressure.

It may be mentioned that the term "oxygen" includes pure oxygen as well as air enriched in oxygen.

In the accompanying drawing forming part of this specification there is shown for purposes of exemplification a preferred form of apparatus in which the invention may be embodied and practised. The drawing shows a diagrammatic flow sheet in vertical section of apparatus for carrying out the improvement provided by the present invention.

The apparatus essentially consists in two equipments, the reaction chamber 1 and the heating and evaporating equipment 2. The walls 3 of the reaction chamber 1 are constructed of refractory material which is heated to a high temperature level by the heat produced in the reaction chamber and which maintains the high temperature in the reaction chamber because of its low thermal conductivity. In the lower part of the reaction chamber 1 a series of recesses 4 having the shape of a truncated cone are provided which open to the reaction chamber. The smaller base of the recesses 4 shows one or more holes which are connected with injector nozzles 5, the latter extending at a short length into the free space of the respective recess. Instead of coordinating one nozzle to each recess it is also possible to provide a series of nozzles forming a bundle, the mouth of the nozzles of each bundle lying in one plane within the hollow of the recess.

Oxygen or air enriched in oxygen is fed through line 6 into the nozzle 5 whilst the liquid fuel after being heated in the equipment 2 is fed through line 7. The flow of oxygen while passing through the nozzle line 5 catches the liquid fuel from line 7, thus forming a homogeneous oil-oxygen mixture which is injected in form of a jet into the reaction chamber. By influence of heat radiation from the hot chamber walls the mixture is ignited and the reaction between fuel and oxygen can take place. The ratio of fuel to oxygen is adjusted in such a way that preferably a combustible gas or a mixture of such gases is formed which naturally has a very high temperature.

The gas mixture produced in this reaction ascends in the reaction chamber and reaches the area of the nozzles 8 at half of the total height of the reaction chamber. The nozzles 8 serve for the introduction into the hot re-

action products from the primary zone of fuel vapours which are fed by line 9. When contacting the hot reaction products the fuel vapours injected by nozzles 8 are likewise heated and then subjected to a thermal cracking process by which process the fuel vapours are cracked forming principally permanent gases, such as hydrogen and carbon-dioxide besides a certain amount of low boiling hydrocarbons such as methane. The combined gas mixture escapes through outlet opening 10 for any use or further treatment. The solid reaction products i. e. ash, elementary carbon, fall down into lowest part of the reaction chamber from which they may be withdrawn continuously or batch wise through opening 11. The pre-treatment of the liquid fuel to be gasified is performed in the heating and evapourating equipment 2. As shown in the drawing the heating and evaporating equipment 2 comprises a fire box 12 and a kettle 13 in which heating and evaporating respectively of the liquid fuels happen. The fire box 12 is equipped with nozzles 14 for injecting an oil-air mixture on gas-air mixture which is ignited and burnt developing a large amount of heat. The burnt or waste gases leave the fire box by ascending through a vertical system of fire or smoke tubes 15 and are gathered in the collector space 16 from which they escape into the chimney stack 17. A throttle 18 in the chimney 17 serves for regulating the draught.

The liquid fuel oil to be treated is fed into the kettle 13 through line 19 and is filled up to a level 20. A free space 21 is provided above the liquid fuel level 20 in the kettle 13. In this free space the fuel vapours from the liquid fuel which has been evaporated by indirect heat exchange with the hot combustion gases from fire box 12 are gathered and then drawn off through line 9 to the injector nozzles 8.

The heated but still liquid fuel oil leaves the kettle 13 through line 7 and is injected after mixing with oxygen from line 6 through nozzles 5 into the recess 4 of the reaction chamber 1.

The temperature of the waste gases in the kettle 13 is adjusted with regard to the desired ratio of liquid fuel to fuel vapour. Moreover the temperature to be maintained must conform to the specific physical and chemical properties of the liquid fuel to be gasified. A most simple manner of regulating the temperature of the waste gases in the fire tubes 15 consists in recycling part of the waste gases of the chimney by line 22 comprising a regulating valve 23 to the fire box 12.

The useful gas is drawn off from the reaction chamber 1 through outlet 10 with a comparatively high temperature. In order to improve the economy of the process according to the invention it has been found advantageous to perform the heating and vaporizing respectively of the liquid fuel in the kettle 13 at least partly by passing the hot useful gases after escaping the reaction chamber 1 through the heating pipes 15 of the kettle 13 before they are used or treated for any purpose.

In case that the fuel to be injected through nozzles 8 should be maintained in a finely divided but still liquid form the equipment 2 seems to be no longer necessary as it is shown in the drawing. In such case the liquid fuel is heated in a suitable apparatus to the desired temperature and afterwards is injected under pressure by the respective nozzles into the reaction chamber.

Having now described the invention and in what manner the same is to be performed it is to be understood that the invention may be variously embodied within the scope of the claims hereinafter made.

What I claim is:

1. A process for the production of combustible gases from fuel which is liquid at ordinary temperatures comprising preheating said fuel, suspending a portion of said preheated fuel in free-oxygen-containing gas, injecting said suspension into a reaction chamber maintained at a temperature above the ignition temperature of said fuel, subjecting at least a portion of said suspended fuel

to ignition and combustion to form hot gaseous combustion products, separately injecting an additional portion of said preheated fuel into the reaction chamber at a point spaced above the point of introduction of said suspension and substantially immediately contacting the additional portion of said preheated fuel with the hot gaseous combustion products, thereby subjecting said additional portion of fuel to cracking, and withdrawing combustible gases from the upper portion of the reaction chamber.

2. The process of claim 1 in which the additional portion of said fuel is injected into the reaction chamber in the form of a liquid spray.

3. The process of claim 1 in which the additional portion of said fuel is injected into the reaction chamber in the form of a vapor.

4. A process for the production of combustible gases from fuel which is liquid at ordinary temperatures comprising the steps of heating said fuel to vaporize a portion thereof, dividing the unvaporized portion into a plurality of streams, injecting the fuel in each of said streams in the form of a suspension in a free-oxygen-containing gas into a reaction chamber maintained at a temperature above the ignition temperature of said fuel, subjecting at least a portion of said fuel from said stream to ignition and combustion to form hot gaseous combustion products, separately injecting the vaporized portion of said fuel into the reaction chamber at a point spaced above the points of introduction of the suspensions and substantially immediately contacting the vaporized portion of said fuel with the hot gaseous combustion products thereby subjecting said vaporized portion to cracking, and withdrawing combustible gases from the upper portion of the reaction chamber.

5. The process of claim 4 in which at least a portion of the preheating of said liquid fuel is accomplished by passing the combustible gases in indirect heat exchange with said liquid fuel.

6. The process of claim 4 in which the vaporized fuel is injected into the reaction chamber in a plurality of streams.

7. The process of claim 6 in which the direction of flow of said streams of vaporized fuel is perpendicular to the direction of flow of said hot gaseous products of combustion.

8. Apparatus for the production of combustible gases from liquid fuel comprising in combination a vertical reaction chamber, a heater adapted to contain and heat said fuel, outlets in the upper and lower portions of said heater, an outlet in the upper portion of said reaction chamber and injector means in the middle and lower portions of said reaction chamber, the upper and lower outlets of said heater being connected to the middle and lower injector means of said reaction chamber respectively and gas inlet means leading into said lower injector means whereby the liquid fuel may be injected into the reaction chamber in the form of a suspension, said lower injector means comprising a plurality of nozzles spaced around the periphery of the reaction chamber.

9. The apparatus of claim 8 in which the outlet end of each of said nozzles is located within a recess in the wall of the reaction chamber, each of said recesses having the shape of a truncated cone, the larger end thereof being adjacent to and opening into the reaction chamber.
